(57) **CLAIM**

The ornamental design for a display screen with graphical user interface, as shown and described.

DESCRIPTION

FIG. 1 is a front view of a display screen with graphical user interface showing our new design; and, FIG. 2 is a front view of the display screen with graphical user interface of FIG. 1 shown within a disclaimed environment. The broken line showing of the remainder of the user interface and display screen is for environmental purposes only and forms no part of the claimed design.

1 Claim, 2 Drawing Sheets

FIG. 1

FIG. 2
